UNITED STATES PATENT OFFICE

DANIEL W. McNEIL, OF CINCINNATI, OHIO.

HAIR-PIN.

No. 873,163.

Specification of Letters Patent.

Patented Dec. 10, 1907.

Application filed June 10, 1907. Serial No. 378,148.

To all whom it may concern:

Be it known that I, DANIEL W. McNEIL, a citizen of the United States of America, and resident of Cincinnati, county of Hamilton, State of Ohio, have invented certain new and useful Improvements in Hair-Pins, of which the following is a specification.

My invention relates to that kind of hair-pin which is provided with a means of holding the short strands of a woman's hair from blowing about her face.

The object of my invention is a hair-pin of this kind which is provided with a ready means for engaging the auxiliary clip or clasp with wisps of short hair, but which is free from rivets and other such attachments in which the hair might become entangled.

Referring to the accompanying drawings, Figure 1 is a front view of a hair-pin embodying my invention. Fig. 2 is a sectional view taken upon line $x-x$ of Fig. 1. Fig. 3 is a view similar to Fig. 1 of a modification. Fig. 4 is a view taken upon line $y-y$ of Fig. 3. Fig. 5 is a front elevation of another modification. Fig. 6 is a sectional view taken upon line $z-z$ of Fig. 5. Fig. 7 and Fig. 8 are respectively front and side elevations of a modification of the hair-pin made with one leg. Fig. 9 and Fig. 10 are views similar to Figs. 5 and 6 of another modification. $s-s$ is section line for Fig. 10.

Referring to Figs. 1 and 2: the part, A, is made similar to an ordinary hair-pin. The clip consists of a flat piece of spring metal with an enlarged central part, b, from which projects jaws, b' , b'' . The clip is secured to the part, a, by having its central portion, b, bent about the curve, a, so as to bring the jaws, b' , b'' , together. The spring in the metal normally holds the jaws, b' , b'' , together.

In use wisps of short hairs are placed between the jaws, b' , b'' , by spreading the jaws apart or by drawing the wisps of hair in between said jaws, the legs of the hair-pin being inserted into the hair in the usual manner.

In the modification shown in Figs. 3 and 4 the clip, C, is made of a flat U-shaped piece 50 of spring-metal from the legs, c , c' , of which

lugs, c^2 , project inward and are bent around the legs of the hair-pin, A, so that the legs, c , c' , of the clip are held by the spring of the metal of the clip in contact with the legs of the hair-pin. The wisps of short hair are to 55 be held in place by being inserted between the legs, c , c' , and the legs of the hair-pin, A.

In the modification shown in Figs. 5 and 6 the clip consists of a flat piece of spring metal having an enlarged part, d, bent around the 60 U-bend, a, of the hair-pin so that the leg, d' , of the clip is held by the spring of the metal in contact with one leg of the hair-pin.

The modification shown in Figs. 7 and 8 is similar to that shown in Figs. 5 and 6, except 65 that the hair-pin, A', has but one leg around the upper end of which the part, d , of the clip is bent, leaving the part, d' , in contact with the leg, A'.

In the modifications shown in Figs. 5—8 70 the wisps of hair are held between the leg, d' , and the leg of the hair-pin.

In the modification shown in Figs. 9 and 10 the clip consists of a flat piece of spring metal in the form of an inverted U, the legs, 75 e , e' , of which have at their outer ends inwardly projecting lugs, e^2 , which are bent around the legs of the hair-pin, so that the free end of the clip is held by the spring of the metal in contact with the upper part of 80 the legs of the hair-pin.

The construction of the hair pin and the clip without the use of rivets and by simply securing the clip by bending it at one of its ends around the wire and having it of a shape 85 such that the spring in the metal only holds the receiving jaw closed, permits of the hair pin being made of a minute form which is known as an invisible hair pin.

It is seen that in use the operation of 90 placing wisps of hair between the jaws of the clip is one that is very easily performed, and that there are no parts of the hair-pin in which hair may readily become entangled.

What I claim is:

1. A hair-pin consisting of a wire and a flat metal clip, said clip consisting of a flat piece of spring metal said clip being secured at one of its ends to the wire by being bent around the same and leaving its opposite end free 100

but normally held by the spring of the metal in the clip against a contiguous part of the hair-pin to form a jaw for receiving wisps of hair.

- 5 2. A hair-pin consisting of a double pronged wire, the prongs being connected at the ends by a U-curve and a flat metal clip

bent at its center about the curve and forming contacting jaws between the prongs for receiving wisps of hair.

DANIEL W. McNEIL.
